Primary Examiner — Manpreet Matharu*Assistant Examiner* — Suzanne Tisdell(74) *Attorney, Agent, or Firm* — Thomas Frost(57) **CLAIM**

The ornamental design for a fishing lure, as shown and described.

DESCRIPTION

FIG. 1 is a left side elevational view of the design for a fishing lure of present invention;

FIG. 2 is a right side elevational view of the fishing lure;

FIG. 3 is a top plan view of the fishing lure;

FIG. 4 is a bottom plan view of the fishing lure;

FIG. 5 is a rear elevational view of the fishing lure;

FIG. 6 is a front elevational view of the fishing lure; and,

FIG. 7 is a sectional view taken substantially along the line 7-7 of FIG. 3.

The broken line showing of a hook and fishing line is for illustrative purposes only and forms no part of the claimed design.
